(57) **CLAIM**

The ornamental design for a cleaning liquid dispenser, as shown and described.

DESCRIPTION

FIG. 1 is an upper perspective view of a cleaning liquid dispenser;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a lower perspective view thereof;

FIG. 9 is an upper perspective view thereof further illustrating an exemplary cleaning liquid cartridge coupled thereto; and,

FIG. 10 is an upper perspective view thereof further illustrating the exemplary cleaning liquid cartridge positioned above the cleaning liquid dispenser before or after coupling the cleaning liquid cartridge thereto.

The broken lines in FIGS. 1 and 6 illustrate parts of the cleaning liquid dispenser that form no part of the claimed design. The broken line showing of the cleaning liquid cartridge in FIGS. 9 and 10 illustrates the environment of the claimed design and forms no part thereof.

1 Claim, 7 Drawing Sheets
